UNITED STATES PATENT OFFICE.

FRANCIS JARVIS PATTEN, OF NEW YORK, N. Y.

DESIGN FOR DICE.

SPECIFICATION forming part of Design No. 25,701, dated June 30, 1896.

Application filed October 1, 1895. Serial No. 564,336. Term of patent 7 years.

To all whom it may concern:

Be it known that I, FRANCIS JARVIS PATTEN, a citizen of the United States, residing at New York, county and State of New York, 5 have invented and produced a new and original Design for Dice and Manner of Designating the Facets of the Same, of which the following is a full, clear, and exact description, reference being had to the accompanying 10 drawings, making part of this specification,

In the drawings, Figures 1 and 2 represent by two views (front and rear) all the details of such a die made according to my design.

The figures show a regular eight-sided solid 15 or octahedron, the six solid angles or apices A A, &c., of which are slightly truncated. Such a die has eight equal faces of approximately triangular form, the corners of the triangles being slightly removed by the truncation of the solid angles. Having eight sides, as described, the dice admit of eight separate 20 designations, instead of six, as usual, and the dice are intended more particularly for the game of "poker dice." I give these eight 25 facets the designations of "playing-cards" from the ace down to the seven spot, inclusive, or any other designation suitable to be used in playing games with dice, as shown in the figures, which represent clearly all eight sides 30 of a single die of my design.

The sides of such a die being triangular in

form, are not well adapted to receive all the ordinary pictorial representations of playing-cards when such are used, but are quite well adapted to receive modified forms of such 35 designations when made to conform to the shape of the face. These modified designations are also original and make a plain and artistic system of marking. Thus the ace is represented in the ordinary way by the usual 40 pictorial representation of an ace. The king, queen, and jack, however, are made to conform to the triangular shape of the face, having a pointed form and but one head, instead of two, as generally shown on playing-cards. 45 For the remaining designations ten, nine, eight, and seven numbers or numerals are used, as indicated. Thus the die is marked partly with the pictorial representations of cards and partly by numbers or numerals. 50

Having thus described the design I have invented, what I claim as my invention is—

The herein-described design for dice.

In testimony that I claim the foregoing as my invention I have hereunto set my hand 55 this 17th day of July, 1895, in presence of two witnesses.

FRANCIS JARVIS PATTEN.
